UNITED STATES PATENT OFFICE.

JAMES C. KIMSEY, OF PHILADELPHIA, PENNSYLVANIA.

LONG-WAIST FORMER.

SPECIFICATION forming part of Letters Patent No. 707,239, dated August 19, 1902.

Application filed November 5, 1901. Serial No. 81,223. (No model.)

To all whom it may concern:

Be it known that I, JAMES C. KIMSEY, a citizen of the United States, and a resident of Philadelphia, in the county of Philadelphia and State of Pennsylvania, have invented certain Improvements in Long-Waist Formers, of which the following is a specification.

This invention is an improvement upon the long-waist former which was patented to me April 9, 1901, No. 671,920; and the object of the present invention is to provide the plate or stay with means whereby the cord which forms the lower part of the frame or former may be doubled to reinforce said frame and the ends of said cord more readily and effectively secured after the device has been properly adjusted.

With the above objects in view the present invention consists in forming the plate or stay with a hook at its lower end and with curved spring members providing tapered slots in which the ends of the cord are firmly held.

In the drawings, Figure 1 is a view showing the application of the improved device. Fig. 2 is an enlarged detail view of the plate or stay. Fig. 3 is an edge view of the plate or stay. Fig. 4 is a detail front view of the lower end of the plate, showing the manner of attaching the cord thereto.

With reference to said drawings, A designates the metal plate or stay, which is adapted to be attached to one of the corset-studs, and B the cord, which is secured to said plate or stay and is held in place thereby to form the part with which the waist or garment engages.

In carrying out my present invention the lower end of the plate or stay A is provided with a forwardly-projecting hook *a* and with a cross-bar *a'* below said hook. The hook is preferably stamped from the plate, as shown, leaving an opening which forms the cross-bar to which the cord is tied, as hereinafter set forth. At a suitable distance above the hook *a* and at each side of the plate is a spring member C, which is separated from the body of the plate by a narrow slit *c*, terminating in an opening *c'*, to give the required resiliency to said member. These spring members are bent or curved forwardly (see Fig. 3) to provide V-shaped slots, in which the ends of the

cord B are wedged and securely held, obviating the necessity of tying said ends and providing a more easy manner of taking up the adjustment of the cord.

55

The plate A is provided with a number of keyhole-slots *a''* to adjust the plate upon the corset, the said slots receiving the ordinary corset-studs.

In the patent hereinbefore mentioned the cord was threaded through slots in the lower end of the plate or stay, and in practice it was found that the cord would pull into the slots and allow the plate to project too far below the cord. It was also found that it was necessary to either provide a heavier cord or double the cord used, and, further, that tying the ends of the cord in a knot failed to keep the adjustment of the device, as the knot was liable to become loose in use. These objections are all removed by improving the metal plate or stay in the manner herein shown and described. The cord is attached to the lower end of the plate by looping said cord upon itself centrally, passing said loop through the opening and around the cross-bar *a'*, and then threading the ends through the loop, as shown in Fig. 4, forming practically two cords which provide the sides of the frame. In applying the device the plate 70 A is placed in engagement with one of the corset-studs. The cords are drawn up over the hips at opposite sides of the plate, passed around the back portion of the waist in opposite directions, and then brought down to 75 the plate for attachment of the ends thereto, whereby the two cords extend in opposite directions entirely around the waist. The ends of the cords are attached to the plate by passing said ends under the hook *a* in opposite 80 directions, leading them up to the V-shaped slots in the sides of the plate, and wedging them in said slots. This provides a very simple and effective means for securely attaching the ends of the cord and also provides for 85 firmly holding the adjustment of the plate.

Having thus described my invention, what I claim as new, and desire to secure by Letters Patent, is—

1. As an improved article of manufacture, 100 a long-waist former, comprising a plate having means for attaching the same to a corset

- or other garment, V-shaped slots in the sides of the plate, and a cord attached to the lower end of the plate, substantially as shown and described.
5. 2. As an improved article of manufacture, a long-waist former, comprising a plate having means for attaching the same to a corset or other garment, a hook at the lower end of the plate, V-shaped slots in the sides of said plate, and a cord attached to the lower end of the plate, substantially as shown and described.

3. As an improved article of manufacture, a long-waist former, comprising a plate having means for attaching the same to a corset or other garment, a hook at the lower end of the plate, a cross-bar, and a cord in looped engagement with the cross-bar, substantially as shown and described.

20 4. As an improved article of manufacture, a long-waist former, comprising a plate having means for attaching the same to a corset or other garment, a hook and cross-bar at the lower end of the plate, and V-shaped slots in the sides of the plate; together with a cord in looped engagement with the cross-bar, sub-

stantially as shown and for the purpose set forth.

5. As an improved article of manufacture, a long-waist former, comprising a plate provided with means of attaching the same to a corset or other garment, a hook stamped from the lower end of the plate, a cross-bar below the hook, and spring members at the sides of the plate curved forwardly to provide V-shaped slots or openings; together with a cord or tape attached to the cross-bar, substantially as shown and for the purpose set forth.

6. As an improved article of manufacture, a long-waist former, comprising a plate having keyhole-slots in its upper end, a hook at its lower end, and V-shaped slots in its sides; together with a cord attached to the lower end of the plate, substantially as shown and described.

In testimony whereof I affix my signature in the presence of two witnesses.

JAMES C. KIMSEY.
